UNITED STATES PATENT OFFICE

2,388,464

AIRPLANE PROPELLER

Bernhard Bergen, Washington, D. C.

Application June 13, 1944, Serial No. 540,069

3 Claims. (Cl. 170—167)

This invention relates to certain new and useful improvements in airplane propellers.

An object of the invention is to provide an airplane propeller preferably constructed of light gauge metal to effect a reduction in the weight of the propeller, the propeller blades per se and the radial arms carrying the same that project from a propeller shaft being of hollow construction.

A further and important object of the invention is to provide an all metal fire-proof screw propeller for an airplane that is designed in a manner to operate with a minimum of noise during rotation thereof.

A still further object of the invention is to provide an airplane propeller of the foregoing character wherein radial arms projecting from a propeller shaft and carrying propeller blades at their outer ends are of tubular pipe-like construction and are adapted to receive a metallic cable which does not materially increase the weight of such arms but provides a reinforcing element for said arms and protection against bullets, shrapnel or the like.

With the above and other objects in view that will become apparent as the nature of the invention is better understood, the same consists in the novel form, combination and arrangement of parts hereinafter more fully described, shown in the accompanying drawing and claimed.

In the drawing:

Figure 1 is a front elevational view of an airplane propeller constructed in accordance with the present invention, the same being partly broken away and shown in section.

Figure 2 is a longitudinal sectional view taken on line 2—2 of Figure 1, showing the spaced wall construction of the propeller blades per se,

Figure 3 is a sectional view taken on line 3—3 of Figure 1 showing the mounting of the propeller per se on one end of a propeller shaft, and

Figure 4 is an end elevational view of the propeller showing the angularly disposed propeller blades per se at opposite ends of the supporting arms.

Referring more in detail to the accompanying drawing, the reference numeral 5 designates the propeller shaft of an airplane that carries at its forward end a transversely extending arm designated in general by the reference character 6 and said arm at its outer ends carries propeller blades designated in general by the reference character 7.

The connection between the supporting arm 6 and the propeller shaft 5 comprises a head mem-

ber formed of a pair of disks 8 and 9 that are connected by an equatorial rib 10 to provide a head structure substantially H-shaped in cross section as shown in Figure 3; but it is to be understood that said supporting head may have the disk portions 8 and 9 thereof selectively formed integral with the rib 10 instead of the unitary structure illustrated. The connection between the supporting head and propeller shaft 5 preferably includes a weld joint 11, but other means of connection may be substituted for such joint.

The arm 6 that extends transversely of the forward end of the propeller shaft 5 is formed of a pair of parallel tubular members 12 and said tubular members at points substantially midway said head and the outer ends thereof are twisted into overlapping relationship as indicated at 13 and have the propeller blades 7 per se secured to the outer ends thereof, with the two propeller blades positioned at desirable relative angles for proper propulsion purposes. As illustrated in Figure 1, the tubular members 12 of the propeller blade supporting arm 6 are spot-welded together as at 14 for the reinforcement of said tubular members in proximity of the twisted portions 13 thereof.

Each propeller blade 7 is of the chambered type and comprises spaced top and bottom walls 15 and 16 with opposite ends deflected toward each other forming relatively sharp ends 16, the open sides of said top and bottom walls 15 and 16 being closed by correspondingly shaped side walls 17, all of said walls being secured together 35 in any appropriate manner as by welding or the like. The outer ends 12a of the tubular members 12 pass through a side wall 17 of the propeller blade 7 and at their terminal ends abut the inner face of the opposite side wall 17, said ends 40 12a being secured to the propeller blade by nut and bolt combinations 18 extending transversely through the top and bottom walls 15 and 16 of the propeller blade and the housed end portions 12a of the tubular members 12, it being understood 45 that other means of attachment may be employed to present smooth uninterrupted surfaces at the outer sides of the walls 15 and 16. As illustrated the leading end 1a of the propeller blade is spaced a greater distance from the connection of the blade with the arm 6 than the trailing end 7b as shown in Figures 1 and 2.

The connection between the arm 6 and head mounting therefor, as shown in Figures 1 and 3, has the rib 10 of the head disposed between the spaced tubular members 12 and the arm is an-

chored to the head by means of the nut and bolt combinations 19 associated with the disk members 8 and 9 of the head at opposite sides of the spaced rib 10, this arrangement of elements providing a strong and substantial support for the propeller blade on the propeller shaft.

The arm 6 and blades 7 are preferably constructed of light gauge metal for the reduction of weight and the particular relative angles of the propeller blades per se results in the operation of the propeller with a minimum of noise. Without materially increasing the weight of the propeller, it is also intended, when occasion requires, to place a solid metallic cable 20 within 15 the tubular members 12 of the arm 6 to provide a reinforcement for said arms and a protection against bullets, shrapnel, and the like.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

I claim:

1. In an all-metal airplane propeller of the character described, and in combination with a propeller shaft, an arm connected to and extending transversely of the forward end of the shaft, a propeller blade mounted on and extending transversely of each of the outer ends of said arm, said arm including a pair of tubular members and said blades being of shell-like form, the connection of said arm with the shaft including a pair of disk-like members, a rib spacing the members and disposed between said tubular members with one of said disks secured to said shaft and nut and bolt combinations carried by said disk members and associated with said tubular member for retaining the latter in position, and a steel cable extending through each tubular member to reinforce the same.

5 2. In an all-metal airplane propeller of the character described, and in combination with a propeller shaft, an arm connected to and extending transversely of the forward end of the shaft, a propeller blade mounted on and extending transversely of each of the outer ends of said arm, said arm including a pair of tubular members and said blades being of shell-like form, the connection of said arm with the shaft including a pair of disk-like members, a rib spacing the members and disposed between said tubular members with one of said disks secured to said shaft and nut and bolt combinations carried by said disk members and associated with said tubular member for retaining the latter in position, and a steel cable extending through each tubular member to reinforce the same, and said tubular member being twisted outwardly of the connection with said shaft to present the propeller blades in relative angular relations.

10 3. In an all-metal airplane propeller of the character described, and in combination with a propeller shaft, an arm connected to and extending transversely of the forward end of the shaft, a propeller blade mounted on and extending transversely of each of the outer ends of said arm, said arm including a pair of tubular members and said blades being of shell-like form, the connection of said arm with the shaft including a pair of disk-like members, a rib spacing the members and disposed between said tubular members with one of said disks secured to said shaft and nut and bolt combinations carried by said disk members and associated with said tubular member for retaining the latter in position, and a steel cable extending through each tubular member to reinforce the same, the outer ends of the tubular members extending into said propeller blades and cross bolts for anchoring said ends therein.

BERNHARD BERGEN.
